(57) **CLAIM**

The ornamental design for a berry harvester catcher, as shown and described.

DESCRIPTION

FIG. 1 is a perspective view of a berry harvester catcher according to the principles of the present invention;

FIG. 2 is a top plan view thereof;

FIG. 3 is a bottom plan view thereof;

FIG. 4 is a front elevational view thereof;

FIG. 5 is a rear elevational view thereof;

FIG. 6 is a left side elevational view thereof; and,

FIG. 7 is a right side elevational view thereof.

The portions shown in broken lines form no part of the claimed invention.

1 Claim, 4 Drawing Sheets(56)
